UNITED STATES PATENT OFFICE.

CLARENCE H. WILEY, OF HARTFORD, CONNECTICUT.

DESIGN FOR A SHOE-SOLE.

SPECIFICATION forming part of Design No. 30,973, dated June 6, 1899.

Application filed April 25, 1898. Serial No. 678,803. Term of patent 14 years.

To all whom it may concern:

Be it known that I, CLARENCE H. WILEY, a citizen of the United States, and a resident of Hartford, in the county of Hartford and State of Connecticut, have invented a new and original Design for Shoe-Soles; and I do hereby declare the following, when taken in connection with the accompanying drawings and letters of reference marked thereon, to be a full, clear, and exact description of the same, and said drawings constitute part of this specification, and represent, in—

Figure 1 a plan view of a shoe-sole, showing my design, and in Fig. 2 a side view of the same.

As shown in the drawings, the leading or material feature of my design consists of a fanciful border *a*, of ornamental stitching, located on the body part *b* of the sole, at or near

the edge thereof, and extending completely 20 therearound, this fanciful border inclosing a raised or central portion *c* on the body part. This central portion conforms to the body part and extends above the upper surface thereof and close to its edge in general outline when seen in plan view and is without 25 ornamentation, the fanciful border forming a frame inclosing said portion.

I claim—

The design for a shoe-sole substantially as 30 shown and described.

In testimony whereof I have signed this specification in the presence of two subscribing witnesses.

CLARENCE H. WILEY.

Witnesses:

ARTHUR B. JENKINS,
GRACE E. METCALF.
